UNITED STATES PATENT OFFICE.

CARL BERG, OF BROOKLYN, NEW YORK, ASSIGNEE TO JAMES W. BEARD, OF NEW YORK, N. Y.

RAIL-TIE.

1,108,682.

Specification of Letters Patent. Patented Aug. 25, 1914.

Application filed December 6, 1913. Serial No. 805,114.

To all whom it may concern:

Be it known that I, CARL BERG, a citizen of the United States, residing at Brooklyn, in the county of Kings and State of New York, have invented new and useful Improvements in Rail-Ties, of which the following is a specification.

The present invention relates to improvements in ties for railway rails.

10 In carrying out my invention I propose to provide a tie which may be constructed entirely of metal, but which will afford the rails the desired amount of resiliency so that danger of the breakage of the tie rails or tie is effectively overcome, and further whereby the tie will embody all of the desirable features of the ordinary wooden tie, while obviating the wear and other disadvantages of the wooden ties.

20 I also aim to construct a metallic tie which will be self sustained against either lateral or longitudinal movement when arranged within the roadbed, and to provide the said tie with a resilient plate which is centrally connected with the tie and which is adapted to have rails secured to the free ends thereof, and so provide elastic or resilient seats for the rails.

30 A further object of the invention is the construction of a tie of this character which shall embody the desirable features of simplicity, thorough effectiveness, strength and cheapness.

35 With the above and other objects in view, which will appear as the nature of the invention is more fully disclosed, the improvement resides in the construction, combination and operative arrangement of parts set forth in the following specification and falling within the scope of the appended claims.

40 In the accompanying drawings there have been illustrated simple and preferred embodiments of the improvement reduced to practice, it being understood, however, that I am not restricted to the precise showing therein illustrated, but that I am entitled to all such changes as fall within the scope of any of the appended claims.

45 In the drawings, Figure 1 is a side elevation of a tie constructed in accordance with the present invention. Fig. 2 is a transverse sectional view upon a line 2—2 of Fig. 1. Fig. 3 is a top plan view of one end of the resilient rail supporting plate. Fig.

4 is a simple longitudinal sectional view taken upon the line 4—4 of Fig. 3, and illustrating a rail secured upon the plate. Fig. 5 is a similar sectional view but illustrating a different means for securing the rail clip to the plates. Fig. 6 is a side elevation of a different form of tie, the rails being secured thereon. Fig. 7 is a sectional view upon the line 7—7 of Fig. 6. Fig. 8 is a top plan view of one end of the rail supporting plate. Fig. 9 is a perspective view of the rail engaging clip. Fig. 10 is a perspective view of the bolt. Fig. 11 is an enlarged sectional view upon the line 11—11 of Fig. 6. Fig. 12 is a side elevation of another form of ties. Fig. 13 is a sectional view upon the line 13—13 of Fig. 12. Fig. 14 is a side view of a still further modified form of the tie.

50 Referring now to the drawings in detail, and to Figs. 1 to 5 in particular, the tie, in its entirety is indicated by the numeral 1. The tie includes a body 2, preferably constructed of metal, and comprising a horizontal straight top 3, downwardly curved sides 4, ends 5 which have their opposite edges angular and which terminate a distance below the sides 2. The body, upon its inner face, is centrally formed with a longitudinal rib 5' which may connect with the ends 5, if desired. Arranged upon the top 3 of the bottom 2, and secured to the central portion thereof is a longitudinal extending flat spring plate 6. This plate is of a length less than that of the body and has its ends bent or otherwise formed to provide rail plans engaging lips 7. The spring plate 6, at a suitable distance from its lips 7, is provided with an opening, the said opening, in Fig. 4, being wedge shaped or having its opposite walls inclined to receive the wedge shaped head 8 of a bolt 9, and the said bolt is adapted to project through an aperture formed in a rail engaging clip 10, and the said clip is sustained upon the bolt and plate 6 in engagement with the inner base flange 100 of a rail 11, through the medium of a suitable nut 12.

55 By reference to Fig. 1 it will be noted that the plate 6 springs upwardly from the tie from its connection with the body 2, and so its rail receiving ends are spaced a suitable and desired distance above the flat top 3 of the body. Thus, it will be noted, the

ends are permitted a certain and desired amount of downward movement when the weight of the rolling stock is deposited thereon, thus, providing the desired amount of flexibility or resiliency to insure the rails against breakage and overcoming any shock or jar which might otherwise be delivered to the rolling stock. If desired wedge members may be arranged beneath the plate 6 upon the top 3 of the body at points adjacent to the central securing members for the plate, so that the ends of the plate will be oppositely elevated the desired distance above the body 2, the said wedges being indicated by the numerals 13. In practice, however, I have found that by constructing the spring bar or plate 6 of the desired thickness and of the proper material the employment of wedges is not necessary, as the said plate is of sufficient strength to have its ends at all times elevated above the body, and even when the weight of the rolling stock is deposited thereon, the ends of the said plate will only slightly contract with the body.

In Fig. 5 the plate 6 is shown provided with a threaded aperture which is adapted to receive the threaded stem of a headed bolt 14, the said bolt having its head bearing upon the upper face of the rail clip 10.

In Fig. 6 the tie bottom 15 comprises a member having an open under face, the ends extending below the sides, and the top being inclined from its center toward both its sides and ends, having inclined corners directed to the sides being indicated by the numerals 16 and those extending to the ends being indicated by the numeral 17. The inclined portions 16 provides the top of the tie bottom with a centrally disposed narrow flat face or rib 18, and secured upon the upper face of the tie, at points adjacent the center thereof is a spring rail receiving plate 19. This plate is of a width equaling that of the tie bottom, and is of a length slightly less than the length of the said body. The plate from its points of connection with the tie body is inclined upwardly or away from the said body toward the ends of the plate. The plate 19 may comprise a flat member having upwardly curved ends, or the said plate may comprise a flat member having its central portion horizontally straight and its ends inclined upwardly from the said straight central portion, and furthermore the ends of the plate upon which the rails are received may be also horizontally straight or in a plane with its central portion.

In order to support the portions of the plate extending beyond the central flat narrow face of the tie body, I provide wedge shaped blocks or bridge members 20, the double faces of which corresponding to the beveled corners 16, upon which they are

adapted to lie, and whereby their upper faces are sustained horizontally straight, and in a plane parallel with that of the horizontal face of the tie body. The members 20 are provided with openings through which pass the securing bolts that retain the plate upon the tie bottom.

The plate 19, at the ends thereof, is provided with substantial rectangular openings 21, arranged in pairs, and the inner edges of the openings communicate with reduced rectangular slots 22. The walls of the slots 22 are beveled outwardly from their upper edges to receive the beveled or inclined walls or sides 23 of bolts 24. The shape of each of the bolts is arranged eccentrically of its head, preferably being positioned adjacent one of the corners of the head, and by such arrangement it will be noted that each of the bolts is susceptible to four different adjustments in accordance with the arrangement of the head of the bolt in its slot 22. The opening 21 is of sufficient size to permit of a head of the bolt being passed therethrough and guided therefrom to within the slot 22 and to have the beveled sides of its head engaged with the beveled walls of the said slot. The rail clips are designated by the numeral 25. These clips, each, comprises a substantially rectangularly body 26 and a rail engaging lip 27. The body, upon its under face, is provided with a lug 28 which is of a size sufficient to fill any one of the openings 21, and the body, at a suitable distance from its lug is formed with an opening 29 through which the shank of one of the bolts passes. The upper face of the clip 25 is provided with an annular boss 30, which surrounds the opening 29, and the said boss on one of its sides, is formed with a depression 31, the side walls of which being inclined upwardly to the face of the boss, and the lower wall being rounded to the side walls. The depression 31 serves as a pocket for a metallic nut lock member 32. The member 32 has a concave upper face and a convex lower face and has its longitudinal sides beveled or inclined, and one of the said sides contacts with one of the beveled or inclined side walls of the depression 31. The convex lower face of the lock 32 lies, for approximately half of the width of the lock, upon the lower curved wall of the depression, but the remainder of the said lower face is raised above the remaining portion of the said lower wall of the depression, and the lock member being of an equal thickness throughout, the upper corner, not contacting with the inclined side wall of the depression is raised above the boss, and provides, what I will term, an engaging tooth 33, which will bite against the lower face of the nut 33' which is provided, one, for each of the bolts. The lock 32 may have its tooth ends compressed with-

in the depression 31 when the nut is screwed in a locking direction, while the tooth 33 will spring into engagement with the nut when the latter is screwed in an unlocking direction.

By providing the body with the inclined surfaces 16 and 17, it will be noted that an accumulation of dirt or ballast of the roadbed will be prevented, and that the spring 10 ends of the plate 19 will not be interfered with while accomplishing their useful function, and it will be further noted that the lugs 28 lock the heads of the bolts within their slots.

In Figs. 12 and 13 the tie body is substantially similar to that just described, with the exception that its inclined longitudinal corners 35 terminate in a point which is disposed centrally of the said tie body. Also, in these figures I provide a single saddle block 36, the under face of which is formed with a longitudinally arranged V-shaped depression 37, whereby the said block may snugly engage with the upper surface of the tie body. The block 36 is disposed centrally of the tie body, and is provided, adjacent its longitudinal sides, with a plurality of openings which serve as passages for securing bolts 38 that pass through registered openings in the inclined top of the tie body. The upper face of the block 36 is horizontally straight and provides a rest for the spring rail receiving and supporting plate 39. The plate 39 is of a width equaling that of the tie body, and is provided with openings through which the securing bolts 38 pass, nuts 40 engaging with the said bolts for locking the plate 39 and the block 36 upon the tie body. By an arrangement as just described a flat horizontally straight spring rail receiving plate may be provided, as the said block 36 elevates the plate a sufficient distance above

the top of the tie to permit of the ends of the plate yielding to the rolling stock.

In Fig. 14 the tie body is provided with an upper face that is horizontally straight at its central portion, as indicated by the numeral 42, and the said upper face inclines downwardly from the straight central portion to the opposite ends of the tie. By this arrangement the spring rail receiving plate 43 may be flat throughout, and its central portion is secured to the central portion of the tie, the beveled portions on the upper face of the tie providing sufficient space for the yielding of the ends of the plate.

From the above description, taken in connection with the accompanying drawings, the advantages of the improvement will, it is thought, be apparent to those skilled in the art to which such invention pertains without further description.

I claim:—

1. A metallic tie having a flat top, sides and ends, the corners of the tie being inclined, a flat spring plate secured centrally to the top of the tie, saddle blocks between the inclined corners and the under face of the plate, said plate having its ends elevated above the tie, means for securing rails to the said ends of the plate.

2. A metallic tie comprising sides, ends extending below the sides and a top which is inclined to its sides and ends, a saddle block arranged centrally upon the inclined top, a flat resilient plate extending longitudinally of the tie and secured to the saddle block, and means upon the opposite ends of the plate for securing rails to the plate.

In testimony whereof I affix my signature in presence of two witnesses.

CARL BERG.
